Patented Aug. 9, 1921.

UNITED STATES PATENT OFFICE.

PHILIP C. FOLWELL, OF VANCOUVER, BRITISH COLUMBIA, CANADA.

UMBRELLA.

1,387,146.

Specification of Letters Patent.

Patented Aug. 9, 1921.

Application filed July 24, 1919. Serial No. 312,880.

To all whom it may concern:

Be it known that I, PHILIP C. FOLWELL, a citizen of the Dominion of Canada, residing at Vancouver, in the Province of British Columbia, Canada, have invented certain new and useful Improvements in Umbrellas, of which the following is a specification.

This invention relates to a means for removably connecting the ribs of an umbrella 10 to the crown of the central stem, and the lower ends of the rib struts to the slidable member by which the umbrella is expanded.

The invention is particularly described in the following specification, reference being made to the drawings by which it is accompanied, in which:

Figure 1 is a perspective view of the upper end of one of the ribs.

Fig. 2, a cross section of the same on the 20 line 3--3 in Fig. 1.

Fig. 3 is a longitudinal section of the crown as connected to the tip of the umbrella "stick" showing the joint of the "stick" thereto as withdrawn.

Fig. 4 is an inverted plan of the crown.

Fig. 5 is a longitudinal section of the stem joint at which the ends of the rib struts are withdrawn from their crown on the slidable member, and

Fig. 6 is an elevation of the central stem or "stick" of the umbrella showing the application of the invention thereto.

The central stem 2 of the umbrella, to the lower end of which the handle is connected, 35 is preferably tubular and adjacent the crown the tubular tip 3 is socketed onto a solid end 4 secured in the end of 2 to project beyond it. This solid end 4 has an annular groove 5 adjacent the joint of the tip connection and 40 secured on the end of the tip to project slightly below the line of the joint with the stem is secured the crown 6, the lower end of which crown is circumferentially grooved as at 7, from the inner side and is radially slotted as at 8 to receive the ends 9 of the 45 several ribs of the umbrella.

The tip 3 with its crown 6 is secured on the projecting end 4 of the stem by a pin 11 through them which pin may also secure the 50 canopy which retains the cover in place.

The upper end of each rib, instead of being apertured to receive the usual wire retaining ring, has a T projection 10. This projection is preferably formed on the end 55 of a piece 9 which is clenched or otherwise secured in the channel of the rib end, see

Figs. 1 and 2. The rib ends 9 are separately inserted, one in each radial groove 8 of the crown before the tip is applied to the central stem and when so applied, and when the 60 crown is applied to the stem 2 the rib ends are retained in position in the groove with free pivotal movement outward within the necessary range. By removing the securing pin 11 and endwise moving the tip 3 to 65 bring the groove 5 opposite the lower lip of the crown groove 7, individual ribs may be removed and replaced.

The lower ends of the rib struts 13 are provided with ends 14 having T projections 70 similar to those 10 of the rib ends. These ends 14 fit in the radial slots 15 of an inner circumferential groove in the upper end of the slidable sleeve or "runner" 16, by which the umbrella frame is extended, in the same 75 manner as those of the crown 6.

Removal of these ends 14 is also effected in a manner similar to that provided in the crown 6. The removal means is at the upper limit of their movement of the runner 80 16 where the stem 2 is socketed at 17, as shown in Figs. 5 and 6. Adjacent the external joint 17 of the socket the projecting portion 18 is provided with a groove 19 which, when the socket is endwise drawn 85 apart to bring the groove opposite the upper edge of the T end retaining groove 15, will permit the removal and replacement of the ends 14.

This socket connection is held in the closed 90 position by a pin 20 secured on the end of the spring 21, to project through a hole drilled in 18, which registers with one in the socket end of 2.

The ends of the ribs and of their struts 95 are by this means connected respectively to the crown and slidable member of the "stick" in a manner that is positive and that they cannot be accidentally displaced, but they can be readily removed for repair or 100 replacement.

Having now particularly described my invention, I hereby declare that what I claim as new and desire to be protected in by Letters Patent is:

1. A means for securing the upper end of the ribs of an umbrella to the crown; said means comprising a stick having a circumferential groove, a crown removably secured on the stick adjacent the groove, the lower edge of which crown is outwardly bent and inturned to form a circumferential groove,

the wall of which is radially slotted, ribs having T ends adapted to fit the slotted groove of the crown, and means permitting endwise movement of the stick in relation to the crown to bring the grooves of stick and crown together and permit removal of the T ends.

2. A means for securing the upper end of the ribs of an umbrella to the crown, said means comprising the combination with a stick the tip of which is removably connected with a socketed joint in the male member of which is a circumferential groove, of a crown secured to one end of the joint connection, the lower edge of which crown is outwardly bent and inturned to form a retaining circumferential groove the wall of said groove being radially slotted, ribs having T ends adapted to fit the groove of the crown through the slots, and means permitting endwise movement of the socket joint to bring the circumferential groove of the male member adjacent the groove of the crown.

3. A means for securing the upper end of

the ribs of the umbrella to the crown and the lower ends of the stretchers to the runner, said means comprising a central stick having socketed joints adjacent the crown and runner in the male member of each of which joints is a circumferential groove, a crown secured to the stick adjacent one socketed joint, a runner endwise movable on the stick, the adjacent edges of which crown and runner are outwardly and inwardly turned to form a circumferential groove in each and radially slotted for the reception of the rib and stretcher ends, ribs and stretchers the ends of which are T shaped and adapted to fit the slotted groove of the crown and runner respectively, means for securing the socketed joints, and means for releasing such securing means that the groove of the male member of each joint may be brought adjacent the groove of the crown and runner respectively.

In testimony whereof I affix my signature.

PHILIP C. FOLWELL.
